UNITED STATES PATENT OFFICE

157,497

COMBINED WALL PLAQUE AND CONDIMENT
SHAKER UNIT

Charles E. Jones, Chicago, Ill., assignor to Commonwealth Plastics, Inc., Chicago, Ill., a corporation of Delaware

Application September 23, 1948, Serial No. 148,734

Term of patent 14 years

(Cl. D44—22)

To all whom it may concern:

Be it known that I, Charles E. Jones, a citizen of the United States, residing at Chicago, in the county of Cook and State of Illinois, have invented a new, original, and ornamental Design for a Combined Wall Plaque and Condiment Shaker Unit, of which the following is a specification, reference being had to the accompanying drawing, forming part thereof.

Fig. 1 is a front elevational view of a combined wall plaque and condiment shaker unit, showing my new design.

Fig. 2 is a side elevational view of same.

Fig. 3 is a top plan view of same.

Fig. 4 is a cross sectional view taken along the line 4—4 of Fig. 1.

Fig. 5 is a sectional view taken along the line 5—5 of Fig. 1.

Fig. 6 is a bottom plan view.

Fig. 7 is a rear elevational view.

I claim:

The ornamental design for a combined wall plaque and condiment shaker unit, substantially as shown.

CHARLES E. JONES.
